To all whom it may concern:

Be it known that I, Elmir J. In corner A, is one fourth of a large wreath of flowers surrounding a small star, 1. Outside of the wreath is a band of small balls, 2, these balls increase in size as they approach the outer edge, which is an irregular solid line. Corner B. is one fourth of a figure composed mainly, of four baskets of flowers, which partly overlap a frame 3, 3. and lace work, 4, 4.

The lower parts of the baskets rest upon --- spring work.

Fig. C, is a plain rosette resting in the centre of a broad band 5, which is composed of small lines, key work and small blocks. Chains of light scrolls extend from corners 6, and 7, to the
